ANTIBACKLASH GEARING

Siegfried W. Larsen, Upper Darby, Pa., assignor
to Leeds and Northrup Company, Philadelphia,
Pa., a corporation of Pennsylvania

Application January 31, 1947, Serial No. 725,496

4 Claims. (Cl. 74—499)

1

This invention relates to means for taking out the backlash in a train of gears and has for an object the provision of anti-backlash means of an improved character and one in which friction is reduced to a minimum.

In anti-backlash devices of the prior art, a spring means of some kind is generally included in the train of gears to bias corresponding sides of the driving teeth against corresponding sides of the driven teeth of the gears. Generally the arrangement includes a pair of gears arranged side by side, the biasing force being oppositely applied to the adjacent gears. In consequence, where they have been rotatably mounted on a stationary shaft, they have operated under high frictional load and thus have required greater power for the transmission of a given amount of torque than is necessary in accordance with the present invention.

In carrying out the present invention in one form thereof, the intermediate gears to which the biasing force is applied in opposite directions comprise intermediate hub assemblies which eliminate the aforesaid high frictional loads. More specifically, the shaft supporting the intermediate gears is mounted in anti-friction bearings. At least one of the intermediate gears is secured to the shaft while the other one is rotatably mounted thereon. In this manner, the application of the frictional force to the bearings is substantially entirely eliminated. It can only be effective when there is relative rotation between the adjacent gears and the design is such that this relative motion rarely occurs during normal operation.

For a more detailed description of the invention, reference may be had to the accompanying drawings, in which:

Fig. 1 is a fractional sectional view of the essential parts of the instrument to which the invention has been applied; and

Fig. 2 is a fractional view taken on the line 2—2 of Fig. 1.

Referring to the drawings, the invention in one form has been shown as applied to a recording and indicating apparatus of the type shown in U. S. Letters Patent No. 2,113,436 to Williams, Jr. Briefly, the recording and indicating apparatus consists of an index 10 movable across a scale 11 simultaneously with movement of a stylus or pen 12 across a strip chart carried by a drum 13 driven by a constant-speed motor, not shown. The carriage 14 for the pen 12 and pointer 10 is driven along a supporting rod 15 by means of a violin string or other suitable driving connection (not shown) from a shaft 16. The shaft 16 is driven

5 by a motor 17 which may be controlled by a measuring network, such as shown in Williams, Jr., U. S. Letters Patent No. 2,367,746. The motor 17, as will be evident from the aforesaid Williams patent, receives a major part of its energization from supply lines and the minor, direction-determining, part from an amplifier. Since power obtained from an amplifier is ordinarily of a low order, it is highly desirable to minimize to as great degree 10 as possible the friction involved in the apparatus driven by the motor. Stated differently, it is relatively expensive to increase the power obtained from amplifiers and the less power that need be obtained to do a given job, the better is the design from the standpoint of initial and operating costs. Another desirable feature of design is to eliminate backlash in the gearing between the driving motor shaft and the shaft which carries the slidewire or impedance-adjusting element. The elimination of the backlash not only insure direct correspondence between movement of the slidewire and the motor, but it also eliminates the production in the measuring circuit of transients or other undesirable disturbances due solely to play or 15 backlash in gearing. Heretofore, anti-backlash arrangements, though eliminating the backlash, have produced high bearing loads resulting in substantial friction in the gearing between the motor and the slidewire shaft.

20 In accordance with the present invention, the friction introduced by the anti-backlash arrangement is greatly reduced over that present in the prior art devices and it is reduced to an amount which is small compared to that normally present 25 in the gearing between the motor drive shaft and the slidewire shaft. More particularly, the motor 17 has mounted on its drive shaft 18 an elongated pinion 19. Two gears 20 and 21 mesh with the gear 19. The gear 20 is rotatably supported 30 on a shaft 22 journaled at its respective ends in anti-friction bearings 23 and 26. The gear 20 is secured to and carried by the hub extension of a pinion gear 25, which is of course free to rotate 35 with respect to the shaft 22. The gear 21 has its hub portion mounted over the hub portion of a pinion 28 and the two are secured to, and rotate with, the shaft 22 by means of a pin 27.

40 Meshing with the pinion gears 25 and 26 are two gears 28 and 29. The gear 28 is secured to the shaft 16 by any suitable means, such as a key, pin or set screw, the latter being shown. The gear 29 is rotatably mounted on the hub 30 of the gear 28, the hub 30 extending upwardly along 45 one side of gear 29 to hold it in position adjacent gear 28 and to present displacement along the 50 55

shaft 16. The shaft 16 supports a variable-impedance device, such as a slidewire 31, and it is also provided with a pulley 32 which, by suitable connection, such as a violin string, not shown, serves to move the pen carriage 14 laterally across the strip chart carried by the drum 13.

As shown in Fig. 2, the gears 28 and 29 are interconnected by spring-biasing means comprising three tension springs 34, 35 and 36. In assembling the gear train, the gears 28 and 29 are rotated with respect to each other to place the springs 34-36 under tension adequate in magnitude to drive the shaft 16 without relative rotation between gears 28 and 29. After assembly and with the motor 17 at standstill, the springs 34-36 are effective on all of the gears between the driving gear 19 and the driven shaft 16. More specifically, the springs bias the meshing teeth of gear 21 into engagement with one side of the teeth of the gear 19. The springs act oppositely on the gear 29 and, therefore, bias the teeth of the gear 20 against the other side of the teeth of gear 19. Thus, as the motor rotates in one direction, there is a direct drive from the elongated pinion 19 through the gear 21, and gears 26 and 28 to the shaft 16. When the motor 17 rotates in the opposite direction, there is a drive from the teeth of gear 19 to the teeth of gear 20 and through gears 25, 29 and the springs 34-36 to the gear 28 and the shaft 16. Since the springs 34-36 have high initial tension, they transmit without further elongation a torque and thus provide the equivalent of a direct drive without backlash for rotation of the drive shaft 16.

Since the initial tension of the springs 34-36 is substantial, the forces applied thereby to the gearing affect the friction developed between the movable parts. With reference to the shaft 22, the gears 28 and 29 apply in opposite directions the force of the springs 34-36 to the shaft 22. If the pinion gears 25 and 26 were both free to rotate on the shaft 22, which would then be held stationary, the opposing forces would create substantial bearing pressures as between the pinions 25 and 26 and the stationary shaft. The high bearing pressure would result in a high frictional load because of the rotation of these gears relative to the stationary shaft. The friction would be present for all movements of the drive shaft 18. However, by mounting the shaft 22 in the bearings or journals 23 and 24 and securing the pinion 26 thereto with the pinion 25 rotatably mounted on the shaft 22, the aforesaid frictional load is to large degree eliminated. During rotation of the drive shaft 18 in either direction, there is no relative movement between pinions 25 and 26 and the shaft 22. Relative movement may occur in event of irregularities in the gear teeth or during transmission of loads beyond the transmission capability of the springs without elongation. The provision of the bearings or journals 23 and 24 at the ends of the shaft and their positions remote from the pinions 25 and 26 which are mounted adjacent to each other, has the further advantageous effect of reducing the bearing load on the journals 23 and 24. Since these are anti-friction bearings, the anti-backlash device of the present invention introduces a negligible additional load on the motor 17.

It may be further observed that the gearing illustrated results in substantial reduction in speed of the driven shaft 16 as compared with that of the motor. Obviously, any desired speed reduction or multiplication may be provided by

suitably changing the diameters of the gears. If greater speed reduction be desired, additional sets of gears may be included which would be provided in pairs with hub assemblies corresponding with the gears 28 and 29 and their associated pinions 25 and 26, though they might be of materially differing diameters. If it is desired to locate the motor at a greater distance from the driven shaft 16 than is shown in Fig. 1, idler gears of desired diameter may be included, the hub assemblies again being the same as for the gears 28 and 29.

While a typical application of the invention has been described, it is to be understood that other modifications may be made within the scope of the appended claims.

What is claimed is:

1. A train of gears having two terminal shafts, one of said terminal shafts having secured thereto a first gear, a second gear rotatably supported on said shaft, spring-biasing means interconnecting said gears and biasing said second gear for rotation with respect to said first gear to take up the backlash of said train of gears, the other of said terminal shafts having an elongated single gear secured thereto, gears intermediate the gears on said terminal shafts, a shaft having secured thereto one of said intermediate gears, and rotatably supporting adjacent thereto another of said intermediate gears, and bearings rotatably supporting said last mentioned shaft in spaced relation from the gears carried thereby.

2. A train of gears having two terminal shafts, one of said terminal shafts having secured thereto a first gear, a second gear rotatably supported on said shaft adjacent said first gear, spring-biasing means interconnecting said gears and biasing said second gear for rotation with respect to said first gear to take up the backlash of the train of gears, the other of said terminal shafts having an elongated single gear secured thereto, speed-changing gears characterized by the substantial reduction of bearing loads imposed by the bias transmitted from said first and second gears comprising gears intermediate, but meshing with, the gears on said terminal shafts, a shaft having secured thereto one of said intermediate gears, and adjacent thereto rotatably supporting another of said intermediate gears, and bearings rotatably supporting said last mentioned shaft in spaced relation from the gears carried thereby.

3. A train of gears having two terminal shafts, one of said terminal shafts having secured thereto a first gear, a second gear rotatably supported on said shaft, spring-biasing means interconnecting said gears and biasing said second gear for rotation with respect to said first gear to take up the backlash of said train of gears, the other of said terminal shafts having an elongated single gear secured thereto, gears intermediate the gears on said terminal shafts and meshing therewith, a shaft supporting intermediate the ends thereof said intermediate gears, bearings for said shaft located adjacent the end portions thereof and at substantial distances from the locations of said intermediate gears, and means for securing one of said intermediate gears for rotation with said last mentioned shaft, another of said intermediate gears being rotatably supported thereon.

4. A train of gears having two terminal shafts, one of said terminal shafts having secured thereto a first gear, a second gear rotatably supported on said shaft, spring-biasing means interconnecting said gears and biasing said second gear

for rotation with respect to said first gear to take up the backlash of said train of gears, one of said terminal shafts having a single gear secured thereto, speed-changing gears characterized by substantial reduction of bearing loads imposed by the bias transmitted from said first and second gears comprising an intermediate shaft, bearings disposed adjacent the ends of said intermediate

shaft for rotatably supporting it, gears intermediate the gears on said terminal shafts supported on said intermediate shaft, at least one of them being rotatable with respect thereto, said intermediate gears being disposed in meshing relation with the gears carried by said terminal shafts.
